UNITED STATES PATENT OFFICE.

FRED S. CARR, OF NEWTON, MASSACHUSETTS.

RUBBER HEEL.

1,274,853.

Specification of Letters Patent.

Patented Aug. 6, 1918.

Application filed November 26, 1917. Serial No. 203,913.

To all whom it may concern:

Be it known that I, FRED S. CARR, a citizen of the United States, residing at Newton, in the county of Middlesex and State of Massachusetts, have invented new and useful Improvements in Rubber Heels, of which the following is a specification.

This invention relates to elastic heels or tread pieces for attachment to the relatively rigid heel portions of shoes, and has for its object to provide a rubber heel, the rear portion of the tread face of which is adapted to be flexed upwardly, so that when the rear portion of the heel strikes the ground or a pavement, and the tread face is in an inclined position, with its forward end raised, the rear portion of the tread face will yield more freely than the main portion thereof, thus suitably cushioning the first impact of the heel.

The invention is embodied in the improvements which I will now proceed to describe and claim.

Of the accompanying drawings forming a part of this specification,

Figure 1 is a top plan view of a rubber heel embodying the invention.

Fig. 2 is a section on line 2—2 of Fig. 1.

Fig. 3 is an enlargement of a portion of Fig. 2.

Fig. 4 is a view similar to Fig. 3, showing the rubber heel held in the position it assumes when the rear portion of the heel tread first strikes the pavement.

Fig. 5 is a view similar to Fig. 3, showing a modification.

The same reference characters indicate the same parts in all of the figures.

In the drawings, 12 represents a rubber heel which, as here shown, is of ordinary construction, and is distinguished from heels now in common use in the particulars hereinafter described, the heel being provided with the usual metallic washers 13 located between its top and tread faces to engage the usual nails 14 which attach the rubber heel to the usual leather heel body 15.

In carrying out my invention, I recess the rear portion of the top face of the heel to a depth preferably equal to about one-half the thickness of the heel, to enable the rear portion of the heel body below the recess portion to be flexed upwardly, said rear portion including the rear portion of the tread face and being of suitable thickness to sustain wear.

In the preferred embodiment of the invention shown by Figs. 1, 2, 3 and 4, the top face of the heel is recessed by forming therein an elongated segmental pocket 16, within and extending parallel with the curved rear wall of the heel, a portion of said pocket being located between the rear washer 15 and the curved rear wall of the heel.

The rear portion of the tread face first strikes the pavement *p* when the wearer is walking, the heel being inclined as indicated by Fig. 4.

It will be seen by reference to Fig. 4, that when the rear portion of the heel, below the bottom of the pocket 16, first strikes the pavement, the said rear portion is flexed upwardly, and at the same time the curved rear wall of the heel is flexed inwardly. The rear portion of the heel including the rear portion of the tread face is therefore adapted to yield with such freedom that the first impact of the heel on a pavement is almost imperceptible. It will also be seen that when the tread face is horizontal, as shown by Fig. 3, its rear portion and the curved rear wall of the heel are returned to their normal positions, the heel presenting the usual external appearance.

In the modification shown by Fig. 5, the rear portion of the heel is provided with a recess 16* which extends to the rear wall of the heel and decreases the height of said wall, there being a space between the rear portion of the rubber heel and the rear portion of the leather heel 15. The rear portion of the rubber heel including the rear portion of the tread face, is therefore adapted to be freely flexed upwardly.

The above-described modification is open to certain obvious disadvantages and is illustrated simply to indicate a possible variation from the construction shown by the preceding figures.

The upwardly flexible rear portion of the heel should be of sufficient thickness to enable it to reasonably sustain wear, said thicknesses here shown being about one-half of the thickness of the body portion of the heel.

It will be seen that the area occupied by the recess 16 and by the flexible rear wall forming the outer side of said recess, is wholly at the rear of the area occupied by the fastening means. In other words, the location of the fastening means is wholly between the portion of the heel which is ren-

dered flexible by the recess and the breast of the heel, so that the flexibility of said portion is not affected by the fastening means.

I claim:

- 5 1. A rubber heel having fastening means and a top face the rear portion of which is recessed to a depth preferably equal to about one-half of the thickness of the heel, to form a flexible rear portion, the said fastening means being entirely between said flexible portion and the breast of the heel, whereby said flexible portion is adapted to be flexed upwardly.
- 10 2. A rubber heel having fastening means and a top face the rear portion of which is

recessed within the curved rear wall of the heel to a depth preferably equal to about one-half of the thickness of the heel, to form a flexible rear portion including the upper part of said rear wall, and the tread portion of the heel below the recessed portion, the said fastening means being entirely between said flexible portion and the breast of the heel, whereby said flexible portion is adapted to be flexed upwardly and the rear wall is adapted to be flexed inwardly.

In testimony whereof I have affixed my signature.

FRED S. CARR.
